UNITED STATES PATENT OFFICE.

HERBERT R. DUCKWALL, OF INDIANAPOLIS, INDIANA.

MOLDING.

1,378,664.

Specification of Letters Patent. Patented May 17, 1921.

Application filed September 3, 1919. Serial No. 321,488.

To all whom it may concern:

Be it known that I, HERBERT R. DUCKWALL, a citizen of the United States, and a resident of Indianapolis, county of Marion, 5 and State of Indiana, have invented a certain new and useful Molding; and I do hereby declare that the following is a full, clear, and exact description thereof, reference being had to the accompanying drawings, in 10 which like numerals refer to like parts.

The object of this invention is to improve, simplify and cheapen leather covered molding such as is used in automobiles and other upholstering and wherein the heads of the 15 tacks or fasteners are concealed.

One feature of the invention is to provide molding with concealed fasteners, without the necessity of multiple core strips.

Another feature of the invention consists 20 in providing a leather covering with a cushion strip secured to the inner surface thereof and formed so as to envelop the outer surface of the core and the head of the fastener embedded therein.

25 The full nature of this invention will be understood from the accompanying drawings and the following description and claims.

In the drawings Figure 1 is a perspective 30 view of a strip of said molding. Fig. 2 is a cross section, on a larger scale, of the core strip and a fastener. Fig. 3 is a cross section, on a larger scale, of the covering. Fig. 4 is a cross section, on a larger scale, of the 35 completed molding.

Said molding has a solid leather core strip 10. As here shown, its inner surface is flat or straight and its outer surface is curved in the arc of a circle so that a cross section of 40 said core strip is in the shape of a segment of a circle, although it is not necessarily limited to said form. The tack or fastener is driven centrally through the core strip at intervals so that the head 12 thereof will 45 be embedded in the core and its outer surface flushed with the outer surface of the core, substantially as shown in Fig. 2.

The covering, shown in Fig. 3, consists 50 of a strip of leather 15 with a cushion pad 16 secured to the inner surface thereof. The pad preferably is formed of thick canvas or other cloth, but is not limited to particular material. The width of the cushion 16 is substantially equal to the width of the outer 55 curved portion of the core and the width of the leather covering portion 15 is substan-

tially the same as the entire width of both the outer curved and inner flat sides of the core.

After the core and fasteners have been 60 secured together as explained, and the covering has been formed as described, the covering is placed on and around the core and secured thereto, substantially as shown in Fig. 4. When thus formed and finished, it 65 is observed that the outer leather portion 15 of the core extends over the curved portion of the core and over the flat inner surface of the core up to the tacks or nails 11, and the pad 16, forming a part of the covering, 70 covers only the curved outer portion of the core with its edges registering and lying alongside of the edges of the core, as shown in Fig. 4. The leather covering 15 is usually made of fine material and is colored to 75 correspond with the upholstering and the cushion 16 thoroughly protects it from the hard solid core and the head of the tack or nail fastener so that said leather covering 16 will wear and preserve its form and 80 beauty for a relatively long time.

There is shown and described herein to 85 illustrate the nature of this invention, a leather core formed of a single piece. The invention is not limited to the material of which the core is made, excepting that it be flexible, nor is it limited to the use of a single layer or ply of material, so long as the fastener extends through the core. Nor 90 is the invention limited to a leather covering, as the covering may be of other material adapted to form the desired surface for the molding.

The invention claimed is:

1. An upholstering molding comprising a 95 flexible core strip, headed fasteners extending through said core strip with their heads flush with the outer curved surface of said strip, a cushion strip of yielding material lying adjacent to and covering the top and sides of the surface of said core strip and the heads of the fasteners, and a surface strip conforming to the curved surfaces of said core strip and cushion strip and surrounding both of said strips for providing 100 the finished outer surface.

2. An upholstering molding comprising a 105 flexible core strip substantially semi-circular in cross section, headed fasteners extending through said core strip having their heads flush with the curved surface thereof, a cushion strip mounted adjacent the curved 110

surface of said core strip and covering the heads of said fasteners, said cushion strip being formed of relatively thin flexible material and extending about the curved surface of said core strip only from one edge to the other, and a surface strip formed of finishing material adapted to surround said cushion strip and conform to the curved

surfaces of both said cushion and core strips, said surface strip being secured around the 10 edges and under said core strip, substantially as described.

In witness whereof, I have hereunto affixed my signature.

HERBERT R. DUCKWALL.
